UNITED STATES PATENT OFFICE.

STILMAN A. HODGMAN, OF WILMINGTON, DELAWARE, ASSIGNOR TO THE LOBDELL CAR WHEEL COMPANY, OF SAME PLACE.

CALENDERING-ROLLS.

SPECIFICATION forming part of Letters Patent No. 387,879, dated August 14, 1888.

Application filed November 21, 1887. Serial No. 255,785. (No model.)

To all whom it may concern:

Be it known that I, STILMAN A. HODGMAN, a citizen of the United States, and a resident of Wilmington, New Castle county, Delaware, 5 have invented certain Improvements in Calendering-Rolls, of which the following is a specification.

The object of my invention is so to construct the frames or housings for holding rolls for 10 calendering paper or for other purposes that any one of the rolls can be removed without disturbing the remainder of the series, as fully described hereinafter.

In the accompanying drawings, Figure 1 is 15 an end view of my improved housing with a stack of rolls for calendering purposes. Fig. 2 is a side view with one of the side frames in section on the line 1 2, Fig. 1; and Fig. 3 is a sectional plan view of one end frame on the 20 line 3 4, Fig. 1, part of the roll being shown in elevation.

A A are the side frames or housings, each having an extension, A', at the base, which has a bed, a, and on the latter is supported one of 25 the bearing-blocks B of the lower calendering-roll, D, the ends d of which are reduced for adaptation to these blocks. The blocks B have lips b b, which overlap the bed a and tend to keep the bearing-blocks in line, and screw-bolts 30 c pass up through the bed and into the bearing-block, thereby firmly securing the block to the bed.

In the face of each frame or housing A is a 35 groove, e, extending from the top of the frame to the recess formed for the reception of the bearing-block of the lower roll, D, this groove being undercut or enlarged at the base, as shown in Fig. 3, for the reception of the heads f of a series of bolts, F, which secure in their 40 proper places each of several boxes G, forming bearings for the upper rolls 1, 2, 3, 4, 5, and 6.

The boxes G are held in place by short plates H, extending from one bolt F to another, recesses being formed in the opposite ends of the 45 plates for the reception of the bolts F. The bolts F are secured to the frame by means of a nut, f'; and a sleeve, g, on each of the bolts acts as a collar and limits the inward movement of the plates H, which are acted on by 50 nuts g' on the bolts F; or the boxes can be held in position by long plates, through which

the bolts pass, and when the plates are removed for the purpose of removing one or more of the rolls the boxes of the remainder of the series can be held in place by means of 55 temporary bolts or clamps.

The calender-rolls rest upon one another; hence it will be seen that so far as regards vertical bearing the rollers support the boxes, the latter, however, serving to retain the rolls in 60 a vertical line.

At each end of the machine a lever, I, pivoted at i to the upper plate, H, bears upon the top box, G, said lever being connected by a rod, i', to a lever, J, pivoted to the frame at j, and 65 is provided with a suitable weight, J', whereby more or less pressure is imparted to the rolls. Suitable bolts, F', pass through the top of each frame A and secure the upper plates, H, to the 70 frames.

In a stack of calender-rolls the lower roll, D, is the prime mover, being connected to the driving-shaft K through the medium of a clutch, M, governed by a suitable hand-wheel, m, and I prefer to provide the center roll with 75 a hand-wheel, n, by means of which it can be rotated when circumstances require it. To remove any one of the rolls—say, for instance, the lower roll—I remove the screw-bolts c and move the roll D, with its bearing-blocks B, out 80 on their beds a until the roll is clear of the frame, first, however, taking off the weight of the roll that is above it by means of wedges or blocks w, driven between the boxes G and the bolts F, as shown by dotted lines in Figs. 85 1 and 2. Tackle is then attached to the roll, which is thus removed from the front of the machine without disturbing the remaining rolls.

By withdrawing the rolls from the front of 90 the machine, instead of endwise, the rolls are not liable to be scratched in removing them. The rolls can be replaced in the same manner.

If one of the upper rolls is to be removed, the weight is taken off the boxes of the roll by 95 wedges or blocks w, placed between the boxes G and bolts F of the roll above, the nuts g', being then unscrewed from the bolts, securing the plates H, which retain the bearing-boxes G of the roll to be removed. The roll, with its bearing-boxes, can then be withdrawn from the front of the machine and taken away, and, if 100

necessary, can be repaired or a new one substituted.

I claim as my invention—

- 5 1. The combination, in a calendering or like machine, of the fixed frames or housings, the series of upper rolls and their boxes, and removable front plates confining said boxes to the frames or housings, all substantially as specified.
- 10 2. In a calendering or like machine, the combination of the upper rolls and their supports with the lower roll and its bearing-blocks, and with the frames or housings having projecting beds, on which the bearing-blocks are mounted, 15 said beds being of such length as to allow the roll to be moved outward until it is clear of the upper rolls, all substantially as described.
- 15 3. The combination of the vertically-grooved frames or housings, the series of upper calendering-rolls and boxes therefor, plates confin- 20

ing said boxes to the frames or housings, and bolts having heads adapted to the grooves of the frames or housings, and nuts for securing the confining-plates, all substantially as described.

4. The combination, in a calendering or like machine, of the vertical frames or housings, the upper series of rolls, retaining-plates therefor, confining-bolts located between the journals of the rolls, and bearing-boxes having on 30 their under sides flattened faces for the action of lifting-wedges, all substantially as specified.

In testimony whereof I have signed my name to this specification in the presence of two subscribing witnesses.

STILMAN A. HODGMAN.
